UNITED STATES PATENT OFFICE

2,481,647

STAPLE REMOVER

William E. de Generes, Sunland, Calif.

Application January 29, 1945, Serial No. 575,130

2 Claims. (Cl. 254—28)

1

This invention relates generally to an implement for removing paper fasteners and to such devices as are designed to remove the ordinary wire staples used to attach several sheets of paper together, being more particularly an improvement on the device shown in my United States Letters Patent No. 2,215,662, issued to me on September 24, 1940.

In the form of device shown in my patent no provision is made for retaining the staple in the device until the staple has been wholly removed from the papers to which it is attached and unless such device is accurately made and care exercised in using the device it sometimes happens that only one side of the staple is wholly removed, necessitating the final removal of the staple by hand, while in other instances the staple will fly away from the paper and possibly strike the person using the device.

To overcome these undesirable features of the device I have provided a clamping member which engages the bridge of the staple and which holds the staple firmly in the device until the operation of removing the staple has been entirely completed.

It is a primary object of the present invention to provide a staple remover of simple form, light in weight, inexpensive and manually operable which is provided with a simple form of clamping device for holding the staple during the operation of removing the staple.

It is also an object of my invention to provide a staple remover of simple form and construction which may be used upon staples of different sizes.

It is also an object of my invention to provide a simple form of staple remover which will not injure the papers during the removal of the staples therefrom.

Other objects and advantages will appear hereinafter from the following description and drawings.

Referring to the drawings, which are for illustrative purposes only:

Fig. 1 is an enlarged side elevation of a staple remover embodying my invention shown in operative relation to a staple and two sheets of material;

Fig. 2 is a side elevation of the device shown in Fig. 1, in the position of the parts as the staple is being removed from the sheets of material;

Fig. 3 is a front elevational view of the device;

Fig. 4 is a top plan view of the device shown in the preceding figures;

2

Fig. 5 is a fragmentary plan view of a modified form of the staple retaining member and adjacent parts; and

Fig. 6 is a fragmentary plan view of the front portion of the device, showing a modified form of toe.

Referring more particularly to the drawings, reference numeral 11 generally indicates the device shown in position on two sheets of material, such as paper, indicated at 12 and through which the staple 13 extends.

To facilitate illustration of the staple remover the device has been shown slightly larger than normal size as is also the staple and sheets of paper. The staples upon which the device is designed to operate include the common wire staple of U-shape, the ends of which when clamped on the sheets of paper fold inwardly against the lowermost sheet of material.

10 The staple remover comprises a primary member 14 which has a base portion 15 and a handle portion 16. The base portion is flat and the handle portion extends upwardly and rearwardly therefrom substantially in the form of an arch.

15 In the form of the invention shown the primary member 14 is formed of a single metal strip which has been cut to the desired pattern and bent to provide upwardly extending side portions or ears 18. In the region of the handle portion the sides have been bent back upon the main body of the member as at 19 in order to provide a flat handle with rounded side edges.

20 The base portion 15 of the primary member 14 is provided with an aperture or cut-out portion 20 for the purposes more fully hereinafter described.

25 The forward flat end of the base portion 15 constitutes what may be termed a toe 21, the inner portion 22 of which is of correct width to slip under the bridge portion of the ordinary staple. This inner portion terminates forwardly in a reduced or narrow portion indicated at 23 which is of correct width to slip under staples of smaller size, this narrow portion being bevelled as indicated at 24 to facilitate the insertion of the toe under the staple.

30 At the juncture of the narrow portion with the inner portion of the tongue, shoulders 26 are provided which, when the device is used for removing small staples, acts as a stop against which such staples engage.

35 A secondary member generally indicated by the numeral 30 is pivotally mounted on the primary member by means of a pin 31 which extends through ear 32 formed on the side portion

33 of said member and through the ears 18 of the primary member. Preferably the member 30 is formed of a single sheet of metal which has been cut to the desired shape and bent to form the side portions 32 and the ear 33 through which the pin 31 extends.

At its outer or forward end the secondary member 30 is provided with what will be termed a tongue portion 34, which is adapted to be accommodated by the aperture or cutaway portion 20 in the toe portion of the primary member 14. In the form of the invention shown this tongue portion 34 is bent at an angle to the main body of the member 30, as is best illustrated in Figs. 1 and 2, and is adapted to fit flush within the base member. It has been pointed out that the toe portion of the primary member is shaped to accommodate the large size staple and also a staple of smaller size, and the tongue 34 on the secondary member is likewise shaped; in other words, with a forwardly extending narrow portion indicated at 35 (see Fig. 4), the tongue just described fitting in the aperture 20 heretofore referred to in the primary member, the side walls of which aperture 20 are shaped to correspond to the edges of the tongue 34.

At the inner end of the tongue the material forming the member 33 is flared outwardly at 37 so as to form a stop means to prevent the tongue from being moved beyond the desired position within the base portion of the member 14.

In order to yieldably hold the members 14 and 33 in the normal position of the device, that is, the position shown in Fig. 1, a spring indicated at 40 is provided, one end of which bears against the underside of the member 33 and the other end of which bears against the upturned portion 41 of a flat spring clamping member indicated at 42, the intermediate portion of the spring bearing against the pin 31, all as illustrated in Fig. 1 of the drawings. It is obvious that any suitable means might be used in place of the particular type of spring shown for yieldably holding the parts of the device in the desired position.

As has been pointed out hereinabove, it is desirable to provide means for retaining the staple in the device until it has been finally extracted from the sheets of paper or other material to which it has been attached and for this purpose I have provided the flat spring clamping member 42 which lies against the inside of the primary member 14, as illustrated in Fig. 1. This clamping member 42 is divided at its forward end into two fingers 43 which are shaped substantially the same as the side portions of the toe 21, forming reduced ends 44, the inner lines of the fingers following the lines of the cutaway portion of the toes. It will be seen, as illustrated in Fig. 4, that the forward reduced ends 44 of the fingers 43 are of such a size as to engage over the smaller size staple indicated in dotted lines at 45, while the wide portion of the fingers engages over a large size staple as indicated in dot and dash lines at 13 in Fig. 4.

In operation the device is used by inserting the toe of the primary member under a staple as shown in Fig. 1, where it will be noted that the fingers 43 of the clamping member extend over the bridge portion of the staple.

The particular shape of the handle portion 16 and the member 33 permits ready manipulation of the device by means of thumb and forefingers. After the toe 24 of the primary member has been inserted under the staple as shown in Fig. 1 the members 14 and 30 are brought together by down-

ward movement of the upper end of member 30 to the position in which the members are shown in Fig. 2, thereby causing the tongue to move upwardly with relation to the base portion and extract and remove the staple as shown in Fig. 2, where it will be noted that the staple is firmly clamped between the fingers 43 of the clamping member and the tongue 34, and after such withdrawal the staple may be manually removed from the device.

In the form of clamping member shown in Fig. 5, the inner lines of the fingers 43 on the clamping member 42 are straight instead of following the lines of the aperture 20 in the toe 21, as shown in Figs. 1 to 4, and the toe indicated at 45 is also straight instead of stepped as shown in the preceding figures. With this construction the clamping member is stiffer than in the form shown in the preceding figures and provides a greater engaging surface for the large staple.

In the form shown in Fig. 6, the tongue 34, toe 21 and spring clamping fingers 43 are shaped merely to accommodate a single size of staple indicated at dot and dash lines by the numeral 50, it being understood, however, that the construction of the remainder of the device is the same as that shown in the form of my invention illustrated in Figs. 1 to 4 inclusive.

Although one form of the invention has been particularly shown and described, it is contemplated that various changes and modifications can be made without departing from the scope of the invention and it is intended to cover such changes and modifications as come within the scope of the claims.

I claim as my invention:

1. A device for removing staples comprising: a primary member having a handle portion and a base portion terminating in a toe having an aperture therein; a secondary member pivotally mounted on said primary member; said secondary member having a tongue portion extending into the aperture in the base portion of the primary member; stop means for limiting the movement of said members in a direction to cause said tongue to pass downwardly through the aperture in the base portion of the primary member beyond the plane thereof; means mounted between the members for yieldingly holding the members with the said tongue portion in the aperture; yieldable staple engaging means spaced apart and extending over the base portion of the primary member at the sides of the tongue on the secondary member; said yieldable staple engaging means comprising a flat yieldable spring metal member extending between the primary member and the secondary member and having forwardly extending fingers extending over the toe portion of the primary member in spaced relation thereto to a sufficient distance to overlie and retain against upward displacement a staple withdrawn by said device.

2. A device for removing staples comprising: a primary member having a handle portion and a base portion terminating in a toe having an aperture therein; said toe terminating in a narrowed portion; a secondary member pivotally mounted on said primary member; said secondary member having a tongue portion extending into the aperture in the base portion of the primary member; said tongue having a forwardly extending narrowed portion and the aperture being shaped to accommodate said tongue; stop means for limiting the movement of said mem-

bers in a direction to cause said tongue to pass downwardly through the aperture in the base portion of the primary member beyond the plane thereof; means mounted between the members for yieldingly holding the members with the said tongue portion in the aperture; yieldable staple engaging means spaced upwardly from and extending over the base portion of the primary member at the sides of the tongue on the secondary member; said yieldable staple engaging means comprising a flat yieldable spring metal member extending between the primary member and the secondary member and having fingers extending forwardly over the toe portion of the primary member, said fingers being spaced from said toe portion a distance to receive a staple between said fingers and said toe yieldably to

clamp the staple to a staple removing element on a staple removing operation of the device.
